ROCK DRILL

Charles F. Osgood, Claremont, N. H., assignor to
 Sullivan Machinery Company, a corporation of
 Massachusetts

Application December 26, 1941, Serial No. 424,426

17 Claims. (Cl. 255—45)

This invention relates to rock drills, and more particularly to improvements in the fluid conducting means of a hammer rock drill of the mounted drifter type.

In hammer rock drills of the mounted drifter type, it is now common practice to effect feed of the fluid actuated hammer motor along the guideways of a guide shell by means of a feed screw journaled on the guide shell and a co-acting feed nut fixed to the drill hammer motor. The feed screw is commonly driven by an independent fluid actuated feeding motor supported at the rear end of the guide shell wholly independently of the drill hammer motor. With such an arrangement, it has been necessary to provide a fluid supply hose connection for the feeding motor in addition to the fluid supply hose for the drill hammer motor. This separate fluid supply hose for the feeding motor hangs down along one side of the drill and is extremely objectionable since it not only becomes entangled, but also due to its exposed location, frequently breaks resulting in a temporary shut-down of the drill.

An object of the present invention is to provide in a rock drill of the above character a novel construction which completely eliminates the separate fluid supply hose connection for the feeding motor thereby, to a large extent, overcoming the disadvantages of previous known devices. Another object is to provide in a mounted drifter type rock drill a self-adjusting fluid supply connection extending longitudinally within the guide shell. A further object is to provide in a rock drill of the above character a telescopic fluid supply means arranged longitudinally within the guide shell in a novel manner. Yet another object is to provide a novel fluid supply arrangement for the feeding motor of a mounted drifter type rock drill, having its control means mounted on the drill hammer motor. A still further object is to provide a mounted drifter type rock drill having an independent feeding motor mounted at the rear end of the guide shell and provided with a fluid supply to the feed motor which is conducted through an element of a drill hammer motor, and including self-adjusting fluid supply connections extending longitudinally within the guide shell. Still another object is to provide novel telescopically arranged fluid supply tube connections for a rock drill. Yet another object is to provide a fluid conducting means for a rock drill having a novel arrangement and combination of parts. Other objects

and advantages of the invention will hereinafter appear.

In the accompanying drawings, in which two illustrative embodiments of the invention are shown:

Fig. 1 is a view partially in side elevation and partially in longitudinal vertical section taken through a hammer rock drill in which the preferred illustrative embodiment of the invention is incorporated.

Fig. 2 is an enlarged cross sectional view taken substantially on line 2—2 of Fig. 1.

Fig. 3 is a detail view in longitudinal vertical section taken substantially on line 3—3 of Fig. 2.

Fig. 4 is an enlarged cross sectional view taken substantially on line 4—4 of Fig. 1.

Fig. 5 is a view in longitudinal vertical section taken substantially on line 5—5 of Fig. 4.

Fig. 6 is a detail cross sectional view taken substantially on line 6—6 of Fig. 5.

Fig. 7 is a horizontal sectional view taken substantially on line 7—7 of Figs. 1 and 2.

Fig. 8 is an enlarged cross sectional view taken substantially on line 8—8 of Fig. 1.

Fig. 9 is an enlarged view taken on line 9—9 of Fig. 1.

Fig. 10 is a view similar to Fig. 1 showing another embodiment of the invention.

Fig. 11 is an enlarged cross sectional view taken substantially on line 11—11 of Fig. 10.

Fig. 12 is a view in longitudinal vertical section taken substantially on line 12—12 of Fig. 11.

Fig. 13 is an enlarged cross sectional view taken substantially on line 13—13 of Fig. 1.

In both illustrative embodiments of the invention, the improved self-adjusting fluid supply connection is embodied in a hammer rock drill of the mounted drifter type, although it will be evident that features of the invention may be embodied in rock drills of other types.

The hammer rock drill comprises a conventional drilling hammer motor 1 mounted to slide along the guideways of a guide shell 2. The hammer motor includes a motor cylinder 3 containing a reciprocable hammer piston for percussively actuating a drill steel 4, the latter being suitably mounted within a front chuck housing 5 secured to the motor cylinder. The motor cylinder is provided with a usual back head 6 carrying a throttle valve mechanism 7 for controlling the supply of pressure fluid from a supply hose connection 8 to the motor cylinder. Journaled on the guide shell is a power driven feed screw 9 which coacts with a non-rotatable feed nut 10 (Figs. 1 and 3), suitably secured to the hammer

motor cylinder. The back head has an opening, rearwardly of the feed nut in alignment therewith, through which the feed screw passes, as shown in Fig. 2. A reversible fluid actuated feeding motor 11, which may be of a conventional design, is mounted in the rear end of the guide shell and has its power shaft operatively connected to the feed screw.

According to the present invention, the back head of the motor cylinder has a laterally located boss 12 projecting within the guide shell and provided with a bore 13 in which is fixed a cylindric tube 14, the latter having its forward end closed by a plug 15. This tube extends longitudinally within the guide shell so as to be protected thereby, in the manner illustrated, and is supported at its forward end within a boss 12 integral with the motor cylinder. Telescopically arranged with respect to this tube is a smaller intermediate tube 16 which, in turn, has telescopic relation with an inner tube 17. The tubes 14 and 16 carry suitable packings 18 and 19 so as to reduce leakage to a minimum. To prevent axial separation of the tubes 14 and 16, the latter has an enlarged front end portion 16', and the inner tube 17 may, if desired, be provided with a similar enlarged front end portion to prevent axial separation thereof from the tube 16. Leading from the supply chamber 20 (Fig. 2) of the throttle valve mechanism 7 is a passage 21 connected to groove 22 in turn connected through radial ports 23 to the interior of the outer tube 14. The interior of this outer tube 14 has communication through the telescopic tubes 18, 19 with a passage 25 leading to a valve mechanism 26 which controls the flow of pressure fluid to the feeding motor. The inner tube 17 has a gland connection at 27 mounted on the casing of the feeding motor 11, and this gland connection permits a limited amount of lateral movement of the tube thereby to prevent the breaking off of the tube in the event the parts are, for any reason, out of exact alignment. This freedom of the lateral movement of the inner tube with respect to the casing of the feed motor also compensates for the vibrations set up within the drill during its operation. The rear flange of the inner tube has a fluid tight seal with the gland plug, and the tube flange may be held in position either by pressure fluid or the coiled spring shown. Due to the particular arrangement of the telescopically arranged tubes longitudinally within the guide shell, an extremely compact structure not only results, but also the tubes are protected to a large extent by the guide shell.

It is accordingly evident that when fluid under pressure is supplied to the supply hose 8 of the drill hammer motor 1, there is a concurrent flow of pressure fluid through passage 21, groove 22, ports 23, through the telescopically arranged tubes 14, 16 and 17 and to passage 25 leading to the control valve mechanism 26 of the feeding motor 11.

The front end of the feed screw 9 is journalled in a bearing bracket 28 (Figs. 8 and 9) suitably attached as by bolts 29 to the front end of the guide shell, and this bracket is so shaped and constructed as to permit the forward portion of the outer cylindric tube 14 to project longitudinally along one side thereof when the drill hammer motor is located in a position near its foremost limit of travel on the guide shell.

The throttle valve mechanism 7 controls the flow of pressure fluid from the supply connection

8 to the hammer motor cylinder 3, and the supply of pressure fluid to the feed motor 11 is controlled by the valve mechanism 26. By reversing the feeding motor 11, the drill hammer motor 1 may be fed in the reverse direction along the shell guideways.

In the embodiment of the invention shown in Figs. 10 to 13, inclusive, a fluid supply connection 30 is mounted on the casing of the feeding motor 11 instead of on the drill hammer motor 1 and the supply of pressure fluid to the hammer motor is conducted through the telescopically arranged tubes 14, 16 and 17. In this instance, the supply chamber 31 of the feed motor control valve mechanism 26 has communication with the supply hose 30, and this chamber is connected by a passage 32 (Fig. 12) to the gland connection 27 for the inner tube 17. The interior of the tube 14 is connected through radial ports 33, groove 34 and passage 35 (Fig. 13) to the supply chamber 20 of the throttle valve mechanism 7. This arrangement enables the positioning of the supply hose for both the feeding motor and the drill hammer motor at the rear end of the guide shell. In this embodiment of the invention, the telescopic tube arrangement is the same as that described above, although, in this instance, fluid flow through tubes occurs in a reverse direction, i. e. from the feeding motor to the drill hammer motor. As in the form of the invention above described, the flow of pressure fluid to the drill hammer motor may be controlled by the throttle valve mechanism 7.

As a result of this invention, an improved fluid supply arrangement is provided for a mounted rock drill of the independent feed motor type, wherein the separate supply hose for the feed motor is completely eliminated. It will further be evident that by arranging the telescopically arranged fluid conducting tubes longitudinally within the guide shell, the arrangement is not only extremely compact, but also the supply tubes are to a great extent protected by the shell. Other advantages of the invention will be clearly apparent to those skilled in the art.

While I have in this application specifically described two embodiments which the invention may assume in practice, it will be understood that these embodiments of the same are shown for purposes of illustration and that the invention may be modified and incorporated in various other embodiments without departing from its spirit or the scope of the appended claims.

What I claim as new and desire to secure by Letters Patent is:

1. In a rock drill, a guide shell, a fluid actuated hammer motor guided on said shell, means for feeding said hammer motor along the shell guideways including a fluid actuated feeding motor mounted on said shell independently of said hammer motor, said hammer motor being movable relative to said feeding motor during the feeding operation, and means for supplying fluid under pressure to said hammer motor and said feeding motor, the fluid supply means for one of said motors including self-adjusting fluid supply connections extending longitudinally within said guide shell intermediate said motors.

2. In a rock drill, a guide shell, a fluid actuated hammer motor guided on said shell, means for feeding said hammer motor along the shell guideways including a fluid actuated feeding motor mounted on said shell independently of said hammer motor, said hammer motor being movable relative to said feeding motor during the

feeding operation, and means for supplying fluid under pressure to said hammer motor and said feeding motor, the fluid supply means for said feeding motor including self-adjusting fluid supply connections extending longitudinally within said guide shell intermediate said motors.

3. In a rock drill, a guide shell, a fluid actuated hammer motor guided on said shell, means for feeding said hammer motor along the shell guideways including a fluid actuated feeding motor mounted in a stationary position at the rear end of said guide shell, and means for supplying fluid under pressure to said hammer motor and said feeding motor, said fluid supply means to one of said motors including self-adjusting fluid supply connections extending longitudinally within the guide shell, said supply connections including a fluid conducting element movable relative to said shell with said hammer motor.

4. In a rock drill, a guide shell, a fluid actuated hammer motor guided on said shell, means for feeding said hammer motor along the shell guideways including a fluid actuated feeding motor mounted in a stationary position at the rear end of said guide shell, and means for supplying fluid under pressure to said hammer motor and said feeding motor, said fluid supply means to said feeding motor including self-adjusting fluid supply connections extending longitudinally within the guide shell, said supply connections including a fluid conducting element movable relative to said shell with said hammer motor.

5. In a rock drill, a guide shell, a fluid actuated hammer motor guided on said shell, means for feeding said hammer motor along the shell guideways including a fluid actuated feeding motor mounted on said shell independently of said hammer motor and relative to which the latter is movable during the feeding operation, said feeding means also including a feed screw journaled on said guide shell and driven by said feeding motor, and means for supplying fluid under pressure to said hammer motor and said feeding motor, said fluid supply means for one of said motors including self-adjusting fluid supply connections extending longitudinally within the guide shell in parallelism with and along one side of said feed screw.

6. In a rock drill, a guide shell, a fluid actuated hammer motor guided on said shell, means for feeding said hammer motor along the shell guideways including a fluid actuated feeding motor mounted on said shell independently of said hammer motor and relative to which the latter is movable during the feeding operation, said feeding means also including a feed screw journaled on said guide shell and driven by said feeding motor, and means for supplying fluid under pressure to said hammer motor and said feeding motor, said fluid supply means for said feeding motor including self-adjusting fluid supply connections extending longitudinally within the guide shell in parallelism with and along one side of said feed screw.

7. In a rock drill, a guide shell, a fluid actuated hammer motor guided on said shell, means for feeding said hammer motor along the shell guideways including a feeding motor mounted in a stationary position at the rear end of said guide shell and relative to which said hammer motor is movable during the feeding operation, and means for supplying fluid under pressure to said hammer motor and said feeding motor, said fluid supply means for one of said motors including telescopically arranged fluid conducting

tubes extending longitudinally within said guide shell, one of said tubes being movable relative to said shell with said hammer motor.

8. In a rock drill, a guide shell, a fluid actuated hammer motor guided on said shell, means for feeding said hammer motor along the shell guideways including a feeding motor mounted in a stationary position at the rear end of said guide shell and relative to which said hammer motor is movable during the feeding operation, and means for supplying fluid under pressure to said hammer motor and said feeding motor, said fluid supply means for said feeding motor including telescopically arranged fluid conducting tubes extending longitudinally within said guide shell, one of said tubes being movable relative to said shell with said hammer motor.

9. In a rock drill, a guide shell, a fluid actuated hammer motor guided on said shell, means for feeding said hammer motor along the shell guideways including a fluid actuated feeding motor mounted on said shell independently of said hammer motor, said hammer motor being movable relative to said feeding motor during the feeding operation, and means for supplying fluid under pressure to said hammer motor and said feeding motor, the fluid supply means for said hammer motor including self-adjusting fluid supply connections extending longitudinally within said guide shell, said supply connections including a fluid conducting element connected to said feeding motor and relative to which said hammer motor is movable.

10. In a rock drill, a guide shell, a fluid actuated hammer motor guided on said shell, means for feeding said hammer motor along the shell guideways including a fluid actuated feeding motor mounted in a stationary position at the rear end of said guide shell, and means for supplying fluid under pressure to said hammer motor and said feeding motor, said fluid supply means to said hammer motor including self-adjusting fluid supply connections extending longitudinally within the guide shell, said supply connections including a fluid conducting element remaining stationary with said feeding motor during feeding movement of said hammer motor relative to said shell.

11. In a rock drill, a guide shell, a fluid actuated hammer motor guided on said shell, means for feeding said hammer motor along the shell guideways including a fluid actuated feeding motor mounted on said shell independently of said hammer motor and relative to which the latter is movable during the feeding operation, said feeding means also including a feed screw journaled on said guide shell and driven by said feeding motor, and means for supplying fluid under pressure to said hammer motor and said feeding motor, said fluid supply means for said hammer motor including self-adjusting fluid supply connections extending longitudinally within the guide shell in parallelism with and along one side of said feed screw.

12. In a rock drill, a guide shell, a fluid actuated hammer motor guided on said shell, means for feeding said hammer motor along the shell guideways including a feeding motor mounted in a stationary position at the rear end of said guide shell and relative to which said hammer motor is movable during the feeding operation, and means for supplying fluid under pressure to said hammer motor and said feeding motor, said fluid supply means for said hammer motor including telescopically arranged fluid conducting

tubes extending longitudinally within said guide shell intermediate said motors.

13. In a rock drill, a guide shell, a fluid actuated hammer motor guided on said shell, means for feeding said hammer motor along the shell guideways including a fluid actuated feeding motor mounted on said shell independently of said hammer motor, said hammer motor being movable relative to said feeding motor during the feeding operation, and means for supplying fluid under pressure to said hammer motor and said feeding motor and a fluid supply connection operatively associated with one of said motors for supplying pressure fluid to both motors, the fluid supply means for one of said motors including self-adjusting fluid supply connections extending longitudinally within said shell.

14. In a rock drill, a guide shell, a fluid actuated hammer motor guided on said shell, means for feeding said hammer motor along the shell guideways including a fluid actuated feeding motor mounted on said shell independently of said hammer motor, said hammer motor being movable relative to said feeding motor during the feeding operation, and means for supplying fluid under pressure to said hammer motor and said feeding motor, the fluid supply means for said feeding motor including self-adjusting fluid supply connections extending longitudinally within said guide shell intermediate said motors and a fluid supply connection operatively associated with said hammer motor for supplying fluid to both of said motors.

15. In a rock drill, a guide shell, a fluid actuated hammer motor guided on said shell, means for feeding said hammer motor along the shell guideways including a fluid actuated feeding motor mounted on said shell independently of said hammer motor, said hammer motor being

movable relative to said feeding motor during the feeding operation, and means for supplying fluid under pressure to said hammer motor and said feeding motor, the fluid supply means for said hammer motor including self-adjusting fluid supply connections extending longitudinally within said guide shell intermediate said motors and a fluid supply connection operatively associated with said feeding motor for supplying fluid to both of said motors.

16. In a rock drill, a guide shell, a fluid actuated hammer motor guided on said shell, means for feeding said hammer motor along the shell guideways including a fluid actuated feeding motor mounted on said shell independently of said hammer motor, said hammer motor being movable relative to said feeding motor during the feeding operation, and means for supplying fluid under pressure to said hammer motor and said feeding motor, the fluid supply means for one of said motors including self-adjusting fluid supply connections extending longitudinally of said guide shell intermediate said motors.

17. In a rock drill, a guide shell, a fluid actuated hammer motor guided on said shell, means for feeding said hammer motor along the shell guideways including a feeding motor mounted in a stationary position at one end of said guide shell and relative to which said hammer motor is movable during the feeding operation, and means for supplying fluid under pressure to said hammer motor and said feeding motor, said fluid supply means for one of said motors including telescopically arranged fluid conducting tubes extending longitudinally of said guide shell, one of said tubes remaining stationary with said feeding motor and another moving with said hammer motor during the feeding operation.
